KITE

Albert W. Gould, 14 Shady Brook Road,
Great Neck, N.Y. 11021

Filed May 6, 1971, Ser. No. 141,082

Term of patent 14 years

Int. Cl. D21—01

U.S. Cl. D34—15

FIG. 1 is a perspective view of the kite pursuant to my new design thereof showing the underside of the kite.

FIG. 2 is a bottom plan view;

FIG. 3 is a top plan view;

FIG. 4 is a front elevational view; and
FIG. 5 is a side elevational view, the opposite side being a substantial mirror image thereof.

I claim:

The ornamental design for a kite, substantially as shown and described.
